(57) **CLAIM**

The ornamental design for a cooking stand as shown and described.

DESCRIPTION

FIG. 1 is a perspective view of our new design for a cooking stand shown in a configuration of use with an environmental fryer;

FIG. 2 is a first side view thereof.

FIG. 3 is a second side view thereof.

FIG. 4 is a back view thereof.

FIG. 5 is a front view thereof.

FIG. 6 is a top view thereof.

FIG. 7 is a bottom view thereof.

FIG. 8 is a perspective view of our new design for a cooking stand shown in isolation for clarity of disclosure;

FIG. 9 is a first side view thereof.

FIG. 10 is a second side view thereof.

FIG. 11 is a back view thereof.

FIG. 12 is a front view thereof.

FIG. 13 is a top view thereof; and,

FIG. 14 is a bottom view thereof.

The portions of the cooking stand shown in broken line form no part of the claimed design. The broken line showing of a fryer in FIGS. 1-7 depicts environment and forms no part of the claimed design.

The shade lines in the Figures show contour and do not claim surface ornamentation or treatment.
